UNITED STATES PATENT OFFICE.

EDWARD JAY McCUTCHEON, OF MEXICO, MEXICO.

AIR-PUMP.

No. 930,781.

Specification of Letters Patent.

Patented Aug. 10, 1909.

Application filed April 10, 1909. Serial No. 489,091.

To all whom it may concern:

Be it known that I, EDWARD JAY McCUTCHEON, of Mexico city, Mexico, have invented certain new and useful Improvements in Air-Pumps; and I hereby declare that the following is a full, clear, and exact description thereof, reference being had to the accompanying drawings, which form part of this specification.

10 This invention has particular reference to the air pumps employed on locomotives for compressing air for braking purposes. These pumps commonly comprise an air or pump cylinder, a steam or motor cylinder in axial alinement with the pump cylinder, and a steam chest on top of the steam cylinder; the pistons in the air and steam cylinders are rigidly connected by a common piston rod; and the steam-valve is 15 actuated by a valve rod extending into the steam cylinder, and engaging a bore in the main piston rod; said rod being engaged by the piston on its ascent, and caused to shift the valve; the valve rod then telescoping 20 into a bore in the piston-rod; and on the descent of the pistons a lug or button on the inner end of rod is engaged by a stop or reversing plate on the piston, whereby the rod is caused to reverse the steam valve,— 25 30 the arrangement being such that the valve is quickly actuated at the proper times by the movement of the main pistons.

When the valve-rod breaks, as sometimes happens, it is necessary among other things, 35 in order to repair the pump as heretofore constructed, to remove the pump from the engine, then remove upper steam cylinder head, then force the piston up as far as it will go and remove reversing plate; then 40 turn pump upside down and let broken portion of rod fall out; the upper part of the rod can be removed by unscrewing a cap-nut above the valve. These operations require tackle, tools and time, and such repairs can- 45 not be made by an engineer when on the road without a great loss of time.

It is the object of the present invention to so improve the construction of such pumps that a broken valve rod can be removed and 50 replaced without taking the pump down, and in such a quick and simple manner that the engineer can readily make the necessary 55 repairs while on the road in very short time and with little trouble. I accomplish this

will now explain, having reference to the accompanying drawings which illustrate a well known form of air-pump, embodying my invention.

In said drawings—Figure 1 is a sectional elevation of an air-pump of the “Westinghouse” type, embodying my improvements. Fig. 2 is an enlarged detail sectional view of a portion of the lower head of cylinder air-piston, piston-rod and threaded plug separated.

In the drawings, A designates the air cylinder; B the steam cylinder; and C the steam chest of an ordinary air-pump for locomotives; a is the air piston; b the steam piston; 70 and c the reversing valve. The pistons a, b, are rigidly connected by a piston rod D which passes through suitable stuffing boxes on the adjacent ends of the cylinders. The cylinder A has the usual air inlet and exhaust 75 ports and connections; and the cylinder B has the usual steam inlet and exhaust ports controlled by the main steam valve c. The valve c is operated by a valve rod E which extends into the steam cylinder, and enters a 80 bore d in the piston-rod D, so that the piston can reciprocate in the steam cylinder without affecting the valve rod E, except near the extremes of the strokes of the piston b. The valve rod E has a button or head e on its 85 lower end, which is retained in the bore d of the piston rod by means of the usual slotted “reversing” plate F attached to the piston b, as shown; and near the valve c the valve rod E is enlarged in diameter, forming a 90 shoulder e'. As the piston b reaches the upper end of its stroke plate F strikes shoulder e and raises the valve-rod, thereby shifting the valve c, and causing the opening of the exhaust port below the piston b, and the 95 steam inlet above the piston; consequently the piston b will be caused to descend. As the piston reaches the end of its downward stroke, plate F catches the button e on the valve rod and draws the latter down, causing 100 it to shift valve c so as to cause the opening of the exhaust above piston b, and admit steam below the piston. Access can be had to the steam valve c by means of a cap-nut or head K in the top of the steam-valve 105 chest, as shown.

The parts thus far described are well known in construction and in operation; the bore d in the piston rod has heretofore been made only sufficiently deep to allow the up- 110

ward movement of the pistons; and if the rod E is broken, the troublesome and extensive operations above noted are requisite in order to replace it. In order to avoid such trouble, expense and delays in replacing a broken valve-rod, I make the following improvements in the construction of the pump. The bore *d* is made continuous throughout the length of piston rod D; its lower end is 10 threaded internally, and is closed by a removable screw plug G which is preferably tapered to insure a steam and air-tight joint. Access can be readily had to this plug G without removing the fastening and locking 15 nuts I usually employ to secure the piston-rod D to piston B. The lower head H of the cylinder A is customarily pocketed or depressed at *h* to accommodate the nuts I, and here I use the opening directly in line with 20 the piston-rod D, and of about the diameter of said piston-rod, and close this opening preferably by a threaded plug J, so that the normal operations of the pump will not be affected, no steam can leak past plug G into 25 the air cylinder; nor air leak through the piston-rod into the steam cylinder. By reason of these simple changes a great saving of time and labor is effected in case it becomes necessary to replace a broken rod,—for then 30 instead of taking down the pump—as above stated—the engineer simply removes plug J, and through its opening has access to plug G, which he can easily remove, whereupon the lower portion of the broken valve rod drops 35 out; then the plugs G and J are replaced. Then the cap K is removed, and the upper part of broken rod removed. Then a new rod E inserted, the lower end of such rod being readily entered into the bore *d* of the piston-rod D by reason of the usual lateral enlargements or slots *f*, *d'*, in the reversing plate F and upper end of rod D,—then cap K is replaced and the pump is in working 40 order once more.

45 Having thus described my invention what I claim as new and desire to secure by Letters Patent is:

1. In an air pump, the combination of a pump cylinder, a motor cylinder, and a valve chest in axial alinement; pistons in said cyl-

inders, a hollow piston rod connecting said pistons, a plug in the end of the piston-rod in the pump cylinder; a valve in the valve-chest, a valve rod connected therewith and extending into the hollow piston-rod, and a plug in the pump cylinder head opposite the plugged end of the piston-rod, substantially as described.

2. In combination, an air cylinder and a steam cylinder in axial alinement, pistons in 60 said cylinders, a piston rod connecting said pistons, and having a bore extending throughout its length, removable means for closing the end of this bore within the air cylinder, an opening in the head of the air cylinder adjacent the end of the piston-rod, means for closing said opening, a valve casing on the upper end of the steam cylinder in axial alinement with the pistons, a valve in said casing, a removable cap for closing the end 65 of the valve chamber, and a valve rod connected with said valve and extending through the steam cylinder and engaging the bore of the piston-rod and means on the steam piston adapted to engage and operate the valve. 70

3. In an air pump the combination of an air cylinder and a steam cylinder in axial alinement, pistons in said cylinder, a piston-rod connecting said pistons and bored throughout its length, a removable plug 80 closing the end of this bore in the air cylinder, an opening in the head of the air cylinder opposite the plugged end of the piston-rod, a plug closing said opening, a valve casing on the upper end of the steam cylinder in axial 85 alinement with the pistons, a valve in said casing, and a valve rod connected with said valve and extending through the steam cylinder and engaging the bore of the piston-rod and having a button on its lower end and a shoulder adjacent the valve, and a retainer plate on the steam-piston adapted to engage the button and shoulder to operate the valve. 90

In testimony that I claim the foregoing as my own, I affix my signature in presence of 95 two witnesses.

EDWARD JAY McCUTCHEON.
